BEAD-STRINGING MACHINES

Max Spool, New York, N.Y.

Application February 15, 1956, Serial No. 565,754

11 Claims. (Cl. 223—48)

This invention relates to a machine for stringing pierced beads, artificial pearls, natural pearls, or other similar pierced articles onto a thread, string, wire, chain, or similar strand.

The principal object of this invention is to provide a ready and simple mechanism that will string beads or similarly pierced items onto thread or wires.

Another object is to provide a bead-stringing machine which works continuously and quickly.

Another object is to provide a bead-stringing machine which requires a minimum of operating care and attention.

With the above and other objects and advantageous features in view, this invention consists of a novel arrangement of parts, more fully disclosed in the detailed description following, in conjunction with the accompanying drawings, and more particularly defined in the appended claims.

In the drawings:

Fig. 1 is a perspective view of an apparatus embodying the invention, some parts being omitted for the sake of clarity.

Fig. 2 is a sectional view taken vertically through the chamber of Fig. 1 on line 2—2 of Fig. 1.

Fig. 3 is an exploded view of one of the shutter assemblies, all shutter assemblies being of similar design and shape but varying in number of holes and in size to fit their respective positions on the chamber.

Figs. 4A and 4B are schematic views of a shutter in the open and closed positions, respectively.

Fig. 5 is a detailed plan view of the top bead-wire supporting clamp, the other clamp being substantially a duplicate.

Fig. 6 is a front elevation view of a bead-wire supporting clamp.

Fig. 7 is a side elevation view of a bead-wire supporting clamp taken on line 7—7 of Fig. 5.

Figs. 8A and 8B are vertical schematic views taken on line 8—8 of Fig. 5 showing a supporting clamp in the open and closed positions, respectively.

Figs. 9A and 9B are plan views of a portion of a bead-wire supporting clamp, showing a set of holes in the open and closed positions, respectively.

The threading of beads, pearls, or similar pierced articles on strings, wires, chains, and the like, presents a problem which has not been solved satisfactorily to date. Machines now available are slow, require much adjustment and manipulation, and then provide only partial satisfaction. This invention provides a simple, foolproof machine which is easy and economical to build and assemble and has been found satisfactory to carry out its work.

A preferred embodiment of the invention has been chosen for purposes of illustration and description and is shown in the accompanying drawings forming a part of the specification.

Briefly, this invention relates to a machine which blows beads upward in a chamber causing these beads to fall

2

over a number of wires and, by chance, to become threaded on these wires. Those beads which are not threaded, are blown up again and the cycle is repeated. This machine also has an arrangement of clamps which permit removing the threaded beads from the chamber and from the machine with a minimum of disturbance to the operation of the system.

Figs. 1 and 2 show a chamber 1 which has a cylindrical section 28, a conical section 29 as its lower part, and cover 9, which contains feed hopper 2. The bottom of this conical section has a bead blower section 5 which consists of a perforated ring-shaped section 30 and a central convex section 31. This bead blower section is fastened to supply line 8 for a supply of gas or liquid under pressure. The conical section 29 contains a number of generally concentric circular rows of holes 27. Over each circle fits a shutter assembly 3. The top of the chamber is closed preferably by an inwardly substantially convex-shaped cover which contains a feed hopper 2. Windows 26 permit the operator to see the action which takes place in the chamber. A number of bead wires 7, which pass individually through the holes in the conical section of the chamber and through holes in the shutter assemblies 3, penetrate the pierced openings 27 of the beads by chance, when the device is in operation. These wires extend downward through the shutter assemblies, which will be described hereinafter. The entire mechanism is supported by a series of supporting legs 6. It is understood that although the drawings show only a few holes 27 and a few wires 7 arranged in a few circles, the invention is not limited to any specific number or arrangement of these elements, except that there will be one wire 7 per hole 27. These wires, it should be further understood, may assume various shapes inside the chamber so as to be more likely to spear the beads.

Each shutter assembly 3, shown in Figs. 1, 2 and 3, consists of two narrow conical sections, the inner one 10 which fits with a rotating sliding motion over a row of holes 27 on the conical section of the chamber, and the outer conical section 11 which fits with a rotating sliding motion on the inner section. Each of these sections has a means, shown as a handle 13, for rotating the section. Each of the conical sections has a series of holes 34 which matches a parallel series of holes 27 in the mating portion of the chamber. All these holes are large enough to permit the beads or other articles which are to be strung to pass through. Each shutter assembly is supported in its appropriate position on the conical part of chamber 1 by means of a sufficient number of suitable brackets 15, which permit rotatably sliding motion of each section of the shutter assembly. The positioning lugs 12 which function with the stop pins 14 limit the rotating motion of the conical sections 10 and 11 from the position where the three mating holes are perfectly aligned (Fig. 4A) to a position (Fig. 4B) where mating holes of a shutter assembly overlap each other sufficiently to allow an opening which would permit a bead wire to pass through but would retain the beads in the chamber, this opening being centered below the mating hole of the chamber. Other types of positioning devices may also be used.

The bead-wire supporting clamp 4, one of which is shown in detail in Figs. 5, 6 and 7, contains a pair of plates 16 and 24 slidably mounted between the flanges 55 of two channel-shaped members 20. On the facing surfaces of plates 16 and 24, near the corners of these plates, are fastened gear racks 22. Gears 21, fastened to axle 17, mesh with the upper and lower racks in the driving side of the bead-wire supporting clamp, this side 65 containing axle 17 which has handle 18. The driven side of this clamp contains idler gears 21', which are fastened to axle 19 and mesh with gear racks 22 at the

driven side of the bead-wire supporting clamp. The ends of axles 17 and 19 pass through holes in the channels 20. A means to limit the sliding motion of these plates is provided, such as stops 23. Rotating motion, imparted to handle 18 is transmitted to axle 17 and gears 21. These gears, through their association with gear racks 22, force the upper plate to slide in one direction and the lower plate in the opposite direction. Gears 21' on axle 19, and their associated gear racks serve as idlers and separators for the driven end of the bead-wire supporting clamp.

Each plate is bored with matching sets of holes 32 and 33. A single set of holes 32 permits passage of supply line 8. A plurality of sets of holes 33 are positioned in the plates so that a single set of these holes is below the holes in the conical section of the chamber and are somewhat larger than the beads to be threaded. Wire clamp pieces 25 are fastened on the bottom face of plate 16, each clamp piece being fastened in such relation in the hole that a portion of the clamp piece protrudes into the opening formed by the hole and mating clamp pieces are similarly fastened to the upper face of plate 24 but are diametrically opposite the respective mating clamp pieces fastened to plate 16. These clamp pieces are such thickness that they essentially occupy the vertical space between the plates 16 and 24 of each bead-wire supporting clamp and still provide a sliding fit between one plate and the wire clamp pieces of the other plate. These pieces are so positioned about a pair of holes that they close in on each other or separate as the plates are moved toward each other or apart. Such a pair of wire clamp pieces is assembled about each pair of holes 33 in each bead-wire supporting clamp. It is these pieces that actually hold the bead-wire and support it in position when the bead-wire supporting clamps are closed, as shown in Figs. 8A, 8B, 9A and 9B. These bead-wire supporting clamps, whether open or closed, do not disturb the position of the wire, as shown in both views of Figs. 8 and 9.

It is thus seen that this invention functions in the following manner. Beads, pearls, artificial pearls, or other similarly pierced articles are placed in the chamber through the feed hopper 2 and rest on the flat, perforated area 30 of bead blower 5. Upon a fluid such as a gas or liquid being blown through the bead blower from supply line 8, the beads are blown and dispersed in an upward direction, impinge on the under surface of the chamber cover 9 and are deflected downward in random fashion, some of the beads falling threaded by chance on wires 7. Those beads which do not get caught, roll or bounce down the inclined interior surface of the chamber and reach the bead blower where they are again blown up to repeat the cycle. These beads are soon all caught by one or another of the many bead wires 7 inside the chamber.

Shutter assembly 3 permits the wires to enter the chamber and prevents the beads from rolling out. When the wires inside the chamber are loaded with the beads, as may be observed through the windows 26, and after the fluid pressure is shut off, these same shutters upon being opened (Fig. 4A) provide a means for allowing the threaded beads to slide down the wire out of the chamber, where they come to rest on the upper bead-wire supporting clamp 4. These shutters may then be closed and more beads may be permitted to enter the chamber through the hopper, and the air or liquid pressure turned on. The upper bead-wire supporting clamp 4 is then opened and the beads slide down to the lower bead-wire supporting clamp. The upper clamp 4 is then closed to hold the wires in position and the lower bead-wire supporting clamp 4 is opened to permit the beads to slide down to the wire, thread, string, or chain which is hooked to the lower end of the bead-wire by conventional means known to those familiar with the art.

By manipulating the feed hopper 2, the shutters 3, the

pressure in supply line 8, and the two sets of bead-wire supporting clamps in appropriate sequence, the operator can maintain a rapid supply of beads being threaded and delivered to the wires or threads at the lower end of the bead wires.

While I have described a specific embodiment of my invention, it is obvious that changes may readily be made in the size, shape, materials, or relative arrangement of parts without departing from the spirit and scope of the invention as defined in the appended claims.

I claim:

1. An apparatus for stringing pierced beads, comprising a chamber for the beads, said chamber having a lower conically shaped section pointing downwardly, said chamber having a plurality of holes arranged in one or more concentric circles in the lower conical section, and a plurality of wires protruding in an upward direction into the chamber through said holes, wire supporting clamps mounted on a supporting structure of said apparatus below said holes for holding the wires, said chamber having fastened thereto a pipe for applying a fluid pressure upwardly against a supply of said pierced beads located in the bottom of the chamber to disperse them upwardly within the chamber, the top ends of said wires positioned in the chamber so that the pierced beads may fall threaded on the wires.

2. An apparatus according to claim 1, the lower section containing a bead blower, said bead blower consisting of a substantially horizontal perforated circular member, the lowest part of said chamber below the bead blower having fastened thereto a pipe supplying gas under pressure.

3. An apparatus according to claim 1, the lower section containing a bead blower, said bead blower consisting of a substantially horizontal perforated ring-shaped section which encloses a rounded convex section, the lowest part of said chamber below the bead blower having fastened thereto a pipe supplying a fluid under pressure.

4. An apparatus according to claim 1 in which the chamber has a filling device consisting of a downwardly facing convex top, said top having a hole therein and a cover over said hole, to drop beads or like materials into the chamber.

5. An apparatus according to claim 1 in which the holes in the lower section, which position the wires and allow the passage of threaded beads out of the chamber, accommodate one wire each.

6. An apparatus according to claim 1 in which the chamber consists of a cylindrical section joined to a conical section, said sections having equal diameters at their juncture, said cylindrical section being mounted on the larger end of the conical section, the smaller end of said conical section pointing downwardly and containing within it a blowing device for dispersing beads upwardly in said chamber by means of a blast of gas or liquid, said plurality of holes arranged in a plurality of circles at various heights in the conical section, said holes each having a single wire to pass into said chamber.

7. An apparatus according to claim 1 in which the chamber has the plurality of holes in its lower section for the positioning of the wires and the passage of threaded beads out of the chamber, said holes accommodating one wire each, each such circle having mounted below and adjacent to it a shutter assembly to retain both threaded and unthreaded beads in the chamber and also to permit threaded beads to slide down said wires out of the chamber at the will of an operator.

8. An apparatus according to claim 1 in which the chamber, having the conical section, has the plurality of holes in the conical section for the positioning of the wires and the passage of threaded beads out of the chamber, said holes arranged in a plurality of circles around the conical section, each circle of holes at a distinct elevation in the conical section, each hole accommodating one wire, a shutter assembly mounted below and ad-

jacent to each said circle of holes to retain threaded and unthreaded beads in the chamber or to permit threaded beads to slide down the wire at the will of an operator, said shutter assembly consisting of two rings which are shaped to fit one over the other, both conforming to the outer surface of the conical section and fastened for individual rotatably sliding motion over a circle of holes, said two rings each having a series of mating holes which can align with the circle of holes in the conical section, a single bead wire passing into the chamber through each set of three mating holes, said shutter assembly permitting threaded beads only to slide down the wire when the shutter is set in the open position and preventing passage of beads when in the closed position.

9. An apparatus according to claim 1, said holes arranged in a plurality of circles at various heights in the conical section, each circle of holes having mounted below and adjacent to it a shutter assembly, each of said shutter assemblies having a number of pairs of matching holes, each pair being associated with and alignable with a single mating hole in the conical section of the chamber, each such set of three holes accommodating a single wire, all wires extending downwardly out of the chamber and through one or more adjustable wire supporting clamps, which support the wires in position and, by the action of an operator, permit the threaded beads to slide down the wire or hold the threaded beads on the wire immediately above the clamp.

10. An apparatus according to claim 9 in which the wires extend downwardly out of the chamber through holes in said chamber and through a shutter assembly and are supported below the chamber by one or more adjustable wire supporting clamps, each clamp comprising two spaced horizontal plates slidably mounted, these

plates containing a series of holes in vertical alignment with the holes in the lower portion of the chamber, said plates having inserts provided between them, two mating inserts per set of mating holes, one insert per hole in each plate mounted on the under side of the upper plate and protruding into the bored-out area of the hole, and the other insert per hole in each plate being mounted on the upper side of the lower plate diametrically opposite its mating insert and also protruding into the hole area, such inserts being so positioned with respect to the sliding motion of the plates that these inserts move toward each other or apart as the plates are moved toward each other or apart, such inserts serving to secure the wire positively when the plates are in the closed position and to permit the wire to remain in its original position but permit passage of threaded beads when the plates are in the open position.

11. An apparatus according to claim 10 in which two adjustable wire supporting clamps are employed to support the wires, one clamp being secured above the other and both supported below the chamber, one clamp being maintained in the closed position while the other is in the open position to permit passage of the threaded beads while keeping the wire in its threading position in the chamber.
